UNITED STATES PATENT OFFICE.

CLIFFTON J. VAN OSTRAND, OF ASHLAND, OHIO.

EARTH-ANCHOR.

1,008,501.

Specification of Letters Patent. Patented Nov. 14, 1911.

Application filed September 21, 1911. Serial No. 650,520.

To all whom it may concern:

Be it known that I, CLIFFTON J. VAN OSTRAND, citizen of the United States, residing at Ashland, in the county of Ashland and State of Ohio, have invented certain new and useful Improvements in Earth-Anchors, of which the following is a specification.

This invention relates to what is commonly known as an earth anchor and with special adaptation to wire fences having long spans between posts, but it is not really limited to fences in its adaptation as it serves as an excellent anchor for other purposes where an anchor of this general character is desirable and when made of a suitable size.

In the accompanying drawings, Figure 1 is a perspective view of the anchor, and Fig. 2 is a face or top view thereof. Fig. 3 is a vertical central sectional elevation showing a wire attached to the loop therein and illustrating in dotted lines the position the anchor assumes when turned or tilted to anchoring position. Fig. 4 is a cross section on line α — α , Fig. 2, and Fig. 5 shows the lower end of the driving bar.

The foregoing illustrations disclose an entirely new and original construction of anchor, the same consisting of a sheet metal embodiment of approximately elliptical shape or outline which preserves all the advantages of a large surface or area for resistance under pull when suitably disposed in the earth and also having a pointed driving point or end and deflecting portions at its top and sides and a laterally extending driving loop at its center adapted to attach the anchor wire. Specifically, the said anchor or plate is fashioned with a driving nose or point 2 having straight converging edges running back or up to approximately one-third its length at either side and terminating in the curved edges of the side wings 3, while the opposite or upper end 4 is formed with straight converging edges like the point 2 and of the same relative length and bent or deflected from the plane of the plate toward the rear or bottom thereof at such angle as may be required to cause the anchor to turn or tilt and assume a horizontal position in the earth when the pull thereon has been sufficient to give it this position.

The side wings 3 have rounded edges running into the said straight edges at both ends

and are further differentiated from the known art by being longitudinally inclined to conform more or less closely to the lines of bend or deflection of the upper deflecting end or wing 4 and adapted to coöperate therewith in turning the anchor in the earth. It will, therefore, be understood that the said side wings are auxiliary to the upper deflecting end 4 in turning the plate to anchoring position. To this end, the said wings are constructed at an inclination which runs from a flush relation with the face of the plate at their lower portions or ends to a depression at their upper portions of approximately a fourth of an inch in depth as further indicated by the lengthwise tapered shoulder or of set 6 at the base of the deflection in each wing. This lateral wing surface on both sides not only aids the upper end 4 in turning or deflecting the anchor in the earth but applies the aid at points where it is most needed and becomes most effective. This is obvious for the reason that the anchor is widest at its middle and hence is the portion which offers the greatest resistance when a turn is to be made. By utilizing a portion of this surface as a deflecting medium the help is applied directly at the point of resistance and the tax upon the comparatively small area of the end 4 is correspondingly reduced. This also enables the anchor to turn more quickly and at greater depth in the earth than would otherwise be possible, which is very material. The face of the anchor has a driving and wire attaching loop 8 struck up from the center thereof and thrown out into circular shape transversely of the plate. The said loop is designed to be made of such proportions as to length, depth and elevation from the face of the plate as to afford room to enter the driving bar 9 within and through the same from above and to make the said bar perfectly rigid with the plate and thereby serve as a guide in driving the plate into the ground. To this end the said bar has a shoulder 10 adapted to engage the edge of said loop, especially at the sides thereof nearest to the surface of the plate, while the point thereof extends through the loop and bears on the flat surface beneath the loop, thus making the said bar serve as an effective guiding and driving member. In this connection it will be observed that the face of the plate is flat throughout except in its 110

wings, and I make the loop deep enough to receive the said bar without depression in the plate. In addition to this I provide the middle of the loop with a transverse depression *a* and with curved edges at said depression or channel to attach the anchoring wire 8 thereto and to hold the wire fixedly at the center of the loop at all times. This construction of the loop makes a segmental formation transversely where the wire is engaged and enables the wire to accommodate itself to the turning of the anchor. This also accentuates the rotation or tilting of the anchor in the earth because it makes an effective leverage apart from the face of the anchor with the side wings as a sort of fulcrum of rotation. How this occurs is plainly seen in Fig. 3 where the wire 7 is shown at the point of leverage on loop 8 while the deflecting point 4 is extending to the other side a corresponding distance, thus materially augmenting the natural tendency of said wings to turn in the earth.

The driving bar 9 has a lengthwise channel *d* on its bottom and side to accommodate itself to the wire in the loop.

By means of the central depression *a* in the loop I prevent the wire from working to either side and hold a central pull under all conditions. This position of the wire is also promoted by the shape of the loop at its bottom edge, the same being cut considerably deeper at its sides than at its middle as shown by the line *c* on which the bottom edge is cut. This makes the loop narrowest at its middle and facilitates the turning of the wire thereon when the anchor is turned and also increases the strength of the loop for driving because the driving is expended upon sides where the loop is deepest.

What I claim is:

1. An earth anchor adapted to be driven into the ground and provided with deflecting portions at its side and top at substan-

tially the same inclination from the plane 45 of the anchor and a driving and wire engaging loop centrally on its face on the opposite side from said deflecting portions.

2. An earth anchor adapted to be driven into the earth and having side wings and a 50 top deflecting portion bent to an inclination to the plane of the anchor and a loop struck from the center thereof opposite the middle of said side wings and constructed to receive a driving bar and a fastening wire at 55 its highest point, whereby easy tilting of the anchor in the earth is effected.

3. An earth anchor of substantially elliptical shape having driving and deflecting portions at its bottom and top respectively and provided with side deflecting wings bent rearward in their outer portions to coöperate with said top deflecting portion and an integral driving loop centrally on the face of the anchor and a wire attached 65 to the middle thereof, said loop having a central depression adapted to confine the wire.

4. An anchor for wire fences and the like having a driving point and deflecting wings 70 and a driving loop at its middle and front deepest at its sides and having its bottom edge inclined upward from its sides and rounded transversely at its middle to attach a wire thereto.

5. An earth anchor having side deflecting wings gradually deepened from their lower 75 to their upper portions and a rearwardly inclined top point and provided with a loop on its face centrally between said wings having 80 its middle portion constructed to attach an anchoring wire thereto.

In testimony whereof I affix my signature in presence of two witnesses.

CLIFFTON J. VAN OSTRAND.
